LOCK CONSTRUCTION

Theodore Karl Remke, Grosse Pointe, and Edwin T. Monet, St. Clair Shores, Mich., assignors to Remke, Inc., Roseville, Mich.

Filed Apr. 6, 1962, Ser. No. 185,701
7 Claims. (Cl. 292—169)

The present invention relates to new and useful improvements in a heavy duty lock construction and more particularly to a heavy duty lock construction for inside mounting on the flat surface of an outside swinging door, such as is found in an armored truck.

In armored vehicles now in use, considerable difficulty has been encountered in the service and maintenance of the door locks (1) because of the excessive number of service parts required, (2) the necessity of having two sets of parts, one for right hand and another for the opposite hand, for use on doors which swing from opposite sides of the door jamb opening.

It is therefore a principal object of the present invention, to provide a simple and durable heavy duty lock construction which will have a very minimum number of parts and will require little or no service maintenance during the life of the vehicle on which the lock is used.

Another object of the invention is the provision of a heavy duty lock construction wherein the bolt is independently operable from either side of the door on which it is mounted, by the use of a knob and or key, the key replacing the knob on the outside, so as to prevent unauthorized entrance into the armored vehicle.

Still another object of the present invention is the provision of a single lock which has common mountings and can be used on right and left hand swinging doors with equal efficiency, without necessity of having to maintain an inventory right and left hand locks.

The above and other objects can be accomplished by the provision of a heavy duty lock construction having a generally hollow housing with substantially flat inner and outer faces; a central machined recess in said hollow housing forming bearing surfaces integral therewith, for guiding a movable, spring loaded rectangular bolt member; a rotational shaft journaled in said housing at generally right angles to said rectangular bolt member; cam surfaces on opposite sides of said rectangular bolt member; a first flat cam having a rapid rise positioned on said rotational shaft, adjacent one of said cam surfaces on said bolt member; a second flat cam positioned adjacent the opposite surface on said bolt member and in alignment therewith, said second flat cam having a slow rise; an elongated opening in said rectangular bolt member intermediate the ends thereof for receiving an independent coupling means, said coupling means adjacent said second flat cam and a second movable member; said first rapid rise cam is operated by a knob secured to said first rotational shaft, while said second slow rise cam is keyed to said coupling means and operated by a key, said slow rise cam providing a mechanical advantage to render the key actuation easy; and a generally flat cover on the inner face of said housing to form a single unitary construction; displacement of either of said flat cam members with the key or knob, each independent of the other, operating to retract the bolt and thereby permit pivotal movement of the vehicle door.

Other objects of this invention will appear in the following description and appended claims, reference being had to the accompanying drawings forming a part of this specification, wherein like reference characters designate corresponding parts in the several views.

In the drawings:

FIGURE 1 is an elevational view of a lock construction which embodies the present invention.

2

FIGURE 2 is a cross sectional view taken substantially along lines 2—2 of FIGURE 1.

FIGURE 3 is a vertical cross section taken substantially along lines 3—3 of FIGURE 1.

5 FIGURE 4 is a rear view of the lock construction shown in FIGURE 1, with the cover member removed, as well as the slow rise flat cam and coupling means.

10 Before explaining the present invention in detail, it is to be understood that the invention is not limited in its application to the details of construction and arrangement of parts illustrated, since the invention is capable of other embodiments and of being practiced or carried out in various ways. Also it is to be understood that the phraseology or terminology employed herein is for the purpose 15 of description and not limitation.

The lock of the present invention is made up of eight major parts, namely the housing, bolt, cover, two cam members, a coupling, a spring for pre-loading the bolt and an actuating handle or knob.

20 Looking at FIGURE 1 of the drawings, we note that the lock housing 10 is of generally rectangular configuration. From FIGURE 2, we note that the housing 10 is of substantially the same uniform thickness. In FIGURE 1, each of the four corners 12, 14, 16 and 18 of the housing 10 are recessed and have located therein generally 25 symmetrical relationship, four openings 22, 24, 26 and 28, each of which is adapted to receive a mounting screw (not shown). The heads of each of the mounting screws (not shown), of course lie below the flat surface 42 of the 30 housing and in the recessed portion, thereby affording a measure of safety for the knuckles, when turning the handle or knob 32.

The handle 32 is of generally T shape and has integral therewith, a generally square shank portion 36. The shank 35 36 extends outwardly from the body portion of handle 32 and is threaded on the outer end 52 thereof. The shank portion 36 is journaled in the housing section 39, which extends outwardly from the generally flat surface 42. The end of the housing section 39 is flat and in substantially parallel relationship to the flat surface 42 above described. The body portion 34 of the handle 32 is also flat as indicated at 44 and engages the flat portion 45 of the housing section 39.

The outer end 52 of the shank portion 36 is threaded 45 and has secured at right angles thereto, a flat cam member 62. The flat cam 62 is keyed to the shank 36 and positioned within the locking housing 10 by a threaded nut 54. The shank 36 and the threaded end portion 52 of shank portion 36 thereof, are of such dimension as to 50 permit free and easy rotation of the flat cam 62, without any possibility of binding.

The bolt member 90 is of generally rectangular cross section and is slidably mounted in the housing 10. Both 55 of the opposed vertical faces 92 and 94 thereof are undercut as illustrated to form cam receiving pockets 92A and 94A. The vertical edges 93 and 95 formed thereby, provide cam surfaces which are cooperable with the operating edge surfaces of each of the flat cams.

The central portion of the bolt 90 has an elongated 60 opening 96 therethrough which is adapted to receive a cylindrical coupling member 140, on which is keyed the second flat cam 102. The inner end of the bolt 90 is generally square with the body portion thereof and has a spring retaining opening 98 centrally located therein, 65 while the outer end of the bolt has a wedge shaped inclined cam surface 99 formed thereon. The spring member 100 at the end of the bolt 90 positions the bolt in contact with the coupling member 140 and flat cams 62 and 102.

70 It will be noted in FIGURES 2 and 3 that the central longitudinal portion 72 of the housing 10 is raised and forms a flat bearing surface on which the flat inner sur-

face 92 of the bolt 90 slides. Additional bearing surfaces 77 and 79 are formed on bosses 73 and 75, substantially perpendicular and square with bearing surface 72, thereby providing accurate and inexpensive bearing surfaces in which the generally rectangular bolt 90 can operate.

The bolt 90 is positioned in the housing 10, between bearing surfaces 77 and 79 respectively and in contact with flat bearing surface 72 in the housing 10. The pocket 92A is located adjacent flat cam 62, with the edge of the flat cam 62 in contact with cam surface 93 on the bolt 90, while nut 54 is received in the central elongated opening 96 in the bolt 90. A compression spring 100 is positioned in the spring retaining opening 98, between the end of the bolt 90 and the end of the housing. By so doing, surface contact between the edge of the flat cam 62 and surface 93 is positively maintained.

Immediately opposite the first flat cam 62 is located the second flat cam 102, which is keyed to a cylindrical coupling member 140 and rotates therewith. The flat cam 102 is adapted to be located in pocket 94A of bolt 90, in the same general manner as is flat cam 62.

The rectangular cover member 110 is generally flat, with the outer edges thereof being located by the recessed edge portion 12 of the housing 10. The inner surface 114 of the cover member 110 forms the bearing surface which guides the last exposed surface 94 of the generally rectangular bolt 90. The cover 110 is secured to the housing 10 with screws inserted through suitable openings therein, which are in alignment with openings 127 and 129 in the bosses 73 and 79 respectively. Openings 127 and 129, of course, are threaded and eliminate the necessity of any loose parts in the housing, which might obstruct the normal operation of the lock mechanism, should they become disengaged.

It will now be readily apparent that independent rotation of either the handle 32, or the coupling 140 with a key, will cause the generally rectangular bolt 90 to retract and move into the housing 10 and that relative motion in either direction will cause same to operate. The first flat cam 62 is operated through the handle 32, while the second flat cam 102 is operated with the cylindrical coupling 140. The flat cam 62 has a rapid rise, while flat cam 102 has a slow rise. This permits a more readily turnable structure when a key is used, because of the mechanical advantage accomplished thereby. Rotation of the cylindrical coupling 140 is made possible by inserting a tang (not shown) of a commercially available lock into the rectangular opening 146 provided therein. Thus, when the lock is mounted a generally flat surface on the outside of the door is provided.

Engagement of the outer cylindrical surface 142 of the coupling 140, with the radial surface 96A in the rectangular bolt 90, as well as engagement of flat cams 62 and 102 with the undercut sections 92A and 94A forms a positive stop for limiting displacement of the bolt. Additionally, the provision of a generally symmetrical flat cam configuration permits operation of the lock with rotational actuation in either direction.

From the foregoing, it is apparent the above described invention is simple, durable and inexpensive. It can be manufactured with modern mass production methods which require a minimum of tooling, resulting in a product which is superior to anything which is now available.

Having thus described our invention, we claim:

1. In a heavy duty lock construction for use on the doors of an armored vehicle, the combination of, a generally rectangular housing, a substantially flat housing cover; a bolt member in said housing, said bolt member of generally rectangular cross section; bearing means in said housing for support of said rectangular cross section bolt member; an elongated opening in said rectangular bolt member, said opening located between the ends thereof and adapted to receive a coupling member therein;

5 a rotatable member extending at right angles to said bolt member and piloted in said housing, said rotatable member in alignment with said coupling member;

10 a first flat cam and a second flat cam, said first flat cam cooperable with and disposed between said bolt and said housing, said second flat cam member disposed between said bolt member and said cover, said rotatable member adapted to operate said first flat cam to retract said bolt member, while said second flat cam, which is independent of said first flat cam, is actuated with said coupling member which is keyed thereto, retraction of said bolt member permitting pivotal movement of said armored vehicle door.

15 2. A lock construction as defined in claim 1, wherein positive stop means are provided to limit displacement of said rectangular bolt when said flat cam members are operated.

20 3. In a heavy duty lock assembly for use on the doors of an armored vehicle, the combination of, a generally hollow housing having a substantially flat

25 mounting surface; bearing means integral with said hollow housing for guiding a spring loaded bolt member;

an elongated opening in said bolt member, said opening disposed between the ends thereof and adapted to receive a coupling member therein;

30 a rotatable member piloted in said housing and extending at right angles to said bolt member, said rotatable member in alignment with said coupling member;

35 a first flat cam and a second flat cam, said first flat cam cooperable with a cam surface on said bolt member, said cam disposed between said bolt member and said housing, said second flat cam cooperable with a second cam surface on said bolt member and disposed between said bolt member and said flat mounting surface;

40 displacement of either of said flat cam members in either direction against their respective cams on the bolt member, independently retracts said bolt member to permit pivotal displacement of said armored vehicle door.

45 4. In a heavy duty lock construction, the combination of,

49 a generally rectangular housing having a flat mounting surface;

50 a machined recess in said housing forming bearings for guiding a generally rectangular bolt member;

55 an elongated opening in said rectangular bolt member intermediate the ends thereof, said opening to receive a coupling member therein;

59 a pair of cam surfaces on said bolt member, said cam surfaces intersecting said elongated opening;

60 a first flat cam positioned in alignment with said coupling member and in contact with said cam surface on said bolt member;

65 a second flat cam positioned in alignment with said coupling member and keyed thereto, with one edge of said flat cam in contact with said cam surface on said bolt member;

69 said first flat cam cooperable with a rotatable member piloted in said housing;

70 displacement of either said first or second flat cam against its respective cam surface on said rectangular bolt member independently retracting said bolt member to render the lock operable.

75 5. In a heavy duty lock construction for use on the doors of an armored vehicle, the combination of, a generally hollow housing having a substantially flat mounting surface thereon; a flat cover on said housing; bearing support means integral with said housing for guiding a bolt member;

a compression spring for pre-loading said bolt member, said spring interposed between the end of the bolt member and the housing;

an elongated opening in said bolt member, said opening located between the ends of said bolt member and adapted to receive a coupling member therein;

a pair of cam surfaces on the outside of said bolt member and intersecting said elongated opening;

a first flat cam and a second flat cam, said first flat cam engaging one of the cam surfaces on the outside of said bolt member, while the second flat cam engages the other cam surface on the bolt, each of the flat cams being in alignment with the coupling member, the first flat cam being independent of the coupling, while the second flat cam is keyed thereto;

said first flat cam cooperable with a rotatable member extending at right angles to said bolt member and piloted in said housing, the rotatable member being in alignment with said coupling member;

- displacement of said first flat cam in either direction retracting said bolt member, rotation of said coupling in either direction also retracting the bolt member, each flat cam being independent of the other.
5. A lock construction in accordance with claim 5, wherein said first flat cam has a rapid rise and said second flat cam has a slow rise.
7. A lock in accordance with claim 5, wherein said cam surfaces on the outside of said bolt operate to positively limit the displacement of said bolt member.
